DESCRIPTION

U.S. PATENT DOCUMENTS

FIG. 1 is a perspective view of a mass transfer packing element showing our new design;

D. 223,701 5/1972 Lausch D25/199
D. 245,999 10/1977 Strigle 261/DIG. 72
D. 281,308 11/1985 Bussey D9/456
D. 337,148 7/1993 Burens D23/207
D. 344,784 3/1994 Swingle D23/209
3,481,455 12/1969 Graham et al. 261/DIG. 72
4,333,893 6/1982 Clyde 261/94
4,425,285 1/1984 Shimoji et al. D23/209
4,575,435 3/1986 Kuhl 261/94

FIG. 2 is a front elevation of the element in FIG. 1;
FIG. 3 is a rear elevation of the element in FIG. 1;
FIG. 4 is a left side elevation of the element in FIG. 1;
FIG. 5 is a right side elevation of the element in FIG. 1;
FIG. 6 is a top elevation of the element in FIG. 1; and,
FIG. 7 is a bottom elevation of the element in FIG. 1.
